Application May 16, 1932, Serial No. 611,546
In France May 20, 1931

23 Claims. (Cl. 250—2)

The present invention relates to improvements in signaling systems using modulated waves and more particularly to systems of this type in which the carrier wave is partly or entirely suppressed at the transmitting station.

In systems of this type heretofore suggested, use has been made of various means to keep the frequency of the locally generated carrier wave at the receiving station in synchronism with the frequency of the suppressed or partly suppressed carrier wave at the transmitting station.

The degree of precision with which the oscillators, at the transmitting and receiving stations, have to be synchronized very rapidly increases when the wave length decreases. For instance, in the case of a wave length of the order of several thousand meters, the necessary precision is of the order of 1/3,000, while in the case of waves of the order of several decameters the necessary precision is of the order of 1/1,000,000.

To synchronize the oscillators employed at the sending and receiving stations, it has already been suggested to make one of the oscillators dependent upon the other by using a pilot frequency transmitted from the sending station for controlling the frequency of the oscillator supplying at the receiving station the carrier frequency used for demodulation purposes. It has also been suggested to compensate for slow variations in the transmission strength of the pilot frequency by providing an automatic regulating amplifier adapted to maintain the pilot frequency at a constant strength. Such systems however have important drawbacks, particularly when used on radio links subjected to fading, since in this case usually the fading phenomena differently affect the frequencies of the signals transmitted and the pilot frequency and distortions result. Further, if, under the influence of fading, the pilot frequency falls below the noise level, the controlled oscillator at the receiving station may undergo undesirable variations in frequency, thus resulting in distortions of the demodulated signals.

It should be noted that in certain signaling systems such as facsimile and television transmission systems on a single side band, it is necessary, not only to keep in synchronism the frequency of the carrier wave at the sending station and the frequency of the local carrier wave generated at the receiving station, but also to keep a constant phase relation between the oscillators at the sending and receiving stations in order to avoid distortions of the wave form of the signals transmitted. It is clear that systems as hereto-

fore proposed do not provide a constant phase relation between the synchronized oscillators.

One of the objects of the present invention resides in overcoming the above mentioned drawbacks; another object consists in providing means for minimizing the influence of fading and for insuring a high degree of quality in a signaling system of the type set forth.

In order to obtain a sufficiently accurate control of the local oscillator at the receiver, in spite of fading of the pilot wave, it is necessary to arrange so that during the periods when the said oscillator is no longer controlled (on account of fading of the pilot wave), the difference of frequencies between the two oscillators must not exceed a limit beyond which the distortion of the transmitted signals would be intolerable; for this purpose, delay net-works or devices may be provided in the path of the pilot wave, in order to prevent the harmful effects of a momentary disappearance of the pilot wave. According to a feature of the present invention, the delay devices provided may be either of constant delay or with variable delay in an intermittent manner, or even of variable delay in a continuous manner, and in the latter case they may be controlled in accordance with one or more of the operative conditions of the signaling system, that is to say in accordance with the fading phenomena to which the system is submitted; the delay devices may be controlled in accordance with the amplitude of the received pilot wave, so as to be very short when the received pilot wave is at a fairly high level, but to be very long when the received pilot wave is at a very low level or when it fades out. The provision of such delay devices in a signaling system of the type set forth is a basic feature, in view of the importance of fading phenomena, particularly in the case of short wave transmission.

The above mentioned pilot wave may consist of one or more frequencies or bands of frequencies (that is to say, frequencies regularly spaced in a band of the frequency spectrum) transmitted to the receiving station, where they are employed to control the operative conditions of the receiver. The pilot signal may be transmitted either in a continuous manner or periodically or at different intervals, during the moments when the signals are not transmitted. Moreover, the position of the pilot signal, particularly when this pilot consists of a plurality of frequencies, should be taken into consideration as well as its relative position with respect to the signal frequency band employed in order to prevent harmful inter-modulation. The pilot signal employed between the

two stations may be a low frequency signal, that is to say a low frequency modulated carrier wave, or even one or more interfering low frequency carrier waves. It should be noted that the term 5 "low frequency" comprises the frequencies which would be produced by a train of impulses.

For example, when a voice frequency band of a width equal to 3000 cycles is transmitted, the 10 pilot signal may be chosen at a frequency of 3,400 cycles for the following reasons:—

(1) The maximum energy in the voice frequency range is in the low frequency zone below 500 cycles; it is consequently desirable to remove the pilot signal as far as possible from these high 15 power frequencies. In order to avoid increasing the width of the frequency band, it has been found convenient to maintain a spacing of 400 to 500 cycles between the transmitted voice frequency band and the pilot signal.

(2) Such signals (voice frequency band and pilot signal) after modulation are displaced in the frequency range by 400 cycles and the result is that when the signals are received on an ordinary receiver, the result is unintelligible, which 20 insures a certain secrecy in the communications.

The pilot wave may be employed in different ways to control the local oscillator provided at the receiver transmitter, for example:—

(1) The pilot wave, after demodulation and amplification, is employed as a local carrier wave, either directly when a portion of the carrier wave of the transmitting station is transmitted, or indirectly by addition or subtraction, with other 30 suitable frequencies.

(2) The pilot wave may be employed to synchronize a local oscillator by acting on one or more of the elements determining the frequency of this local oscillator.

In order to obtain a constant phase relation 40 between the synchronized oscillators, advantage may be taken of a property of coupler oscillators consisting in this that, when a synchronizing frequency interacts with an oscillator of approximately the same frequency, the oscillator will, under certain conditions, tend to adjust itself to oscillate at the same frequency as the applied synchronizing frequency. It may be noted that the phase relation of the applied frequency and 50 that of the oscillator should bear a certain definite relation so that the oscillations are stable. When it is desired to have a phase relation very finely adjusted, this may be done by providing in the output circuit of the oscillator any suitable type of phase correcting circuit such as, for instance, a tuned circuit which may be slightly detuned, the degree of detuning of this circuit being controlled so as to obtain the required fine phase adjustment.

As the amount of control provided by the synchronizing frequency varies substantially linearly with the amplitude of the synchronizing frequency, it is accordingly necessary to provide a gain control equipment adapted to keep the amplitude of the synchronizing frequency constant. Since in the case of wireless transmission the pilot wave may fade out entirely during a very large number of cycles of the controlled oscillator, the latter may drift in frequency to such an extent that the constant phase relation may be lost, this resulting in intolerable distortion. In this case, advantage may be taken of the fact that fading does not in general equally affect the various frequencies transmitted and accordingly a plurality of pilot frequencies may be

used so that if one of these pilot frequencies fades out, the remaining pilot or pilots will maintain constant the frequency and phase relation of the controlled oscillator. Since the pilots are necessarily of different frequencies, it is necessary to provide at the receiving station means adapted to bring the frequency and phase relation of the pilots at a constant value corresponding to that of the oscillator used at the transmitting station. This may be done by means of separate oscillators, for instance, in the case of two pilots, the frequency of the second pilot is brought back to that of the first by means of a separate oscillator controlled exactly in frequency and phase by the beat note between the two pilots.

It should be noted that when one of the pilots fades out the beat note vanishes and it is therefore necessary to provide a time constant of sufficient value so that the oscillator controlled by the note does not alter its frequency by more than a predetermined amount, that is to say, a small fraction of one cycle. This is possible in the case of a low frequency oscillator because one cycle of its frequency corresponds to a large number of cycles of the carrier wave, whereas it 25 would be impossible if this method were applied directly on the resupplied carrier frequency. The time constant of the low frequency oscillator is chosen so that, in the absence of the beat note, the oscillator will drift in frequency at the rate of say 30 one tenth of a cycle per second or less. Another reason for using a low frequency oscillator controlled by the beat note is that the frequency and phase relation of the beat note vary much more slowly than those of the pilot frequencies.

As the amount of control depends upon the amplitude of the controlling frequency, and as the amplitude of each one of the pilots may be affected by fading, it may be necessary to provide a gain control equipment for controlling 40 separately and independently the amplitude of the controlling beat note.

Broadly, according to the present invention, the effect, in a system of the type set forth, of the pilot frequency or frequencies on the controlled oscillator, is adapted to depend upon the amount of attenuation imposed on the signal by fading phenomena to which the system is subjected for instance means (e. g. delay networks with variable delay, retarded gain control equipment controlling the amplitude of the pilot, since the amount of control depends upon the amplitude of the pilot) may be provided and adapted to delay suitably and according to fading conditions the action of the pilot frequency or frequencies on the controlled oscillator, so that a constant frequency and/or phase relation are (or is) maintained between the synchronized oscillators. Since the average volume of the signal transmitted may not be affected by fading conditions attenuating the pilot wave to an extent of say 40 to 50 decibels, it is often necessary to provide a quick acting gain control equipment in the path of the pilot wave and a comparatively slow acting gain control equipment in the path 65 of the signals.

In order to show clearly the nature and various aspects of the invention, a detailed description of a transmission system employing features of the invention will be given hereinafter with 70 reference to the accompanying drawings in which:—

Fig. 1 shows a single side band transmission system for short waves;

Fig. 2 shows the corresponding receiving sta- 75

tion in which means are provided to maintain a constant frequency relation between the oscillators at the transmitter and at the receiver;

Fig. 3 represents a receiving system in which means are provided for maintaining a constant frequency and phase relation between the oscillators at the transmitting and receiving stations.

The transmitter shown in Fig. 1 is a transmitter rendering it possible to transmit in a radio signaling system a single sideband approximately without distortion. The signals, for example, a telephone conversation, are applied to a transmitter TT whose current is amplified by means of a low frequency amplifier BFA. The amplified currents leaving BFA pass through a band-pass filter F₁ permitting the transmission of a frequency band comprised, for example, between 0 to 3 kilocycles. The frequency band thus obtained is applied to a balanced modulator MD₁, which is associated with a suitable oscillator OSC₁, whose frequency is chosen in such a manner that among the products of modulation of the balanced modulator MD₁ there is a modulation band comprised, for example, between 16 and 19 kilocycles, corresponding to the signals to be transmitted. This band is filtered by means of a second filter F₂.

In parallel on the output of the filter F₂ is an oscillator OSC₂ followed by an attenuator ATT which enables currents of the frequency of the oscillator OSC₂ but of suitable amplitude to be applied in the output circuit of the filter F₂. The currents produced by this oscillator serve as a pilot wave.

The oscillator OSC₂ may have a frequency outside the frequency band passed by the filter F₂. The combined output of the filter F₂ and the oscillator OSC₂ is applied to an amplifier A₂ before being applied to a second balanced modulator MD₂ which is associated by means of a coupling stage C₁ with a suitable oscillator OSC₃.

Among the modulation products of the modulator MD₂ those are chosen by means of a filter F₃ which correspond to a band of frequencies comprised, for example, within the limits of 265 to 269 kilocycles.

This band of frequencies is amplified by means of a suitable amplifier A₃ whose currents are applied to a harmonic generator employed at the same time as modulator HGM. On the input circuit of the harmonic generator modulator HGM are applied the frequency produced by the master oscillator MOSC by means of a coupling circuit C₂ and the frequency band representing the signals to be transmitted and the pilot signal or signals provided by the amplifier A₃. The apparatus HGM comprises an arrangement of vacuum tubes somewhat similar to an ordinary harmonic generator, but this apparatus is moreover adapted to operate at the same time as modulator. The object of the apparatus HGM is to modulate a suitable harmonic of the oscillations produced by the master oscillator MOSC with the output of the amplifier A₃, the arrangement being such that the corresponding side bands with or without carrier wave, that is without the considered harmonic of the frequency of the master oscillator, are found in the output circuit of said apparatus HGM. It is as a rule preferable to suppress the carrier wave in the output circuit of the apparatus HGM by employing for the latter a balanced vacuum tube arrangement.

For example, when a single vacuum tube is em-

ployed as harmonic generator, the amplitude of the desired harmonic produced varies according to the grid bias of the tube, and it is possible to find a region in which the output of the tube varies substantially linearly with the grid bias. If, now the biasing potential of the grid be adjusted so as to correspond approximately to the middle of the linear portion of this characteristic, and if the output of the amplifier A₃ be then applied to the grid, it will be seen that the amplitude of the desired harmonic will vary linearly with the instantaneous voltage supplied by the amplifier A₃; in other words, the output of the amplifier A₃ is linearly modulated by said desired harmonic. It will be noted that this harmonic is a harmonic of the oscillations produced by the master oscillator MOSC associated with the apparatus HGM. Consequently the currents supplied by the apparatus HGM contain the frequencies supplied by A₃ modulating the desired harmonic of the master oscillator MOSC, that is to say the carrier wave. It is possible by employing an arrangement of balanced vacuum tubes for the apparatus HGM, to suppress the harmonic itself (that is to say the carrier wave) in its output circuit, and to keep only one or two of the modulation side-bands corresponding to this harmonic.

A filter F₄ is provided at the output of the apparatus HGM to choose the desired side-band; this side-band contains the various frequencies supplied by the apparatus A₃ and particularly the pilot wave produced by the oscillator OSC₂.

In order to obtain the necessary power, a series of power amplifiers such as the amplifiers PA₁, PA₂, PA₃, are provided and associated with the transmitting antenna AT. It will thus be seen that the system which has just been described permits of the transmission in the case of short waves of a single side-band accompanied by a pilot wave allowing, as will be seen in the following, the control at the receiving station of the operative conditions of the oscillator employed at this station to reproduce the carrier wave of the transmitting station. The harmonic generator modulator apparatus is based on the fact that the operation of a tube as modulator and as generator is made on the same portion of the characteristic and consequently the same tube may be employed for the two functions.

At the receiving station the received signals are applied to a receiving antenna AR and thence to a high frequency amplifier HFA, whose current is applied to a first detector DEC₁ associated with a beat frequency oscillator controlled by quartz OSC₄. The output of the detector is applied to an intermediate amplifier AMI₁ whose output is applied to a band filter BF. An attenuator ATT is provided to control easily the power level in the output circuit of the filter BF. This attenuator being followed by a second intermediate amplifier AMI₂ whose current is applied to a second detector DEC₂, an amplifier A₁ if provided after this detector and a filter F₁ enables the frequency band applied to the demodulator DEM associated with the oscillator OC₁ to be limited.

Among the demodulation products produced by the demodulator DEM, a filter F₂ enables the desired band to be transmitted; this filter is followed by a low frequency amplifier ABF to which is connected an ordinary telephone receiver TR.

The system shown in Fig. 2 also permits the use of the pilot wave transmitted to the transmitting station so as to control the operative

conditions of the beating oscillator OSC_b associated with the second detector DEC_2 . Moreover, automatic means permitting of the gain control of the system are provided and associated with 5 the first and second detectors or demodulators.

The pilot wave is selected in the output circuit of the detector DEC_2 by means of a filter F_3 . The frequency of this pilot signal is displaced in the frequency spectrum so as to occupy, for example, 10 the position corresponding to 4 kilocycles per second, by means of an oscillator OSC associated with the detector DEC_4 . The output of this detector DEC_4 is amplified by the amplifier A_2 whose output is filtered by means of a filter F_4 of very 15 sharp cut-off frequency. The output of the filter F_4 is applied in parallel to two apparatuses F_5 and F_6 which are such that their attenuation curve in function of the frequency is cut in the present case at 4 kilocycles, the curves having 20 opposite slopes on each side of the point of intersection, so that if the frequency provided by F_4 increases by a small amount the voltage applied to the balanced detector $BDEC_1$ is increased while that of the detector $BDEC_2$ is diminished. 25 A slight reduction in the frequency would have an opposite effect. The voltage of F_5 and F_6 is applied to the grids of the tubes $BDEC_1$ and $BDEC_2$, so that corresponding rectified currents are produced in the output circuits of these tubes 30 and the difference of potential between two points of this circuit will be positive or negative according to the direction of variation of the frequency beyond or on this side of 4 kilocycles. This difference of potential is applied through a circuit CR damping the rapid variations and which may also have a certain time constant; thence the corresponding current is applied to an apparatus APP associated with the oscillator OSC_b and adapted to control in a compensatory manner the frequency of the oscillator OSC_b at the time of a 35 change in the current supplied by the apparatus CR . It will be noted that in the present case it is not desired to change the amplitude of the pilot signal to produce a change in the difference of control potential produced by the apparatus $BDEC_1$ and $BDEC_2$. Moreover, if it were possible to employ detectors and filters F_5 and F_6 perfectly balanced, a change of amplitude of the pilot signal would not produce a change in the voltage 40 of the point S_2 when the pilot signal is exactly at the frequency of 4 kilocycles, the voltage of the point S_2 would only be modified during the fluctuations of the frequency of the pilot signal on both sides of the mean value of 4 kilocycles. In 45 practice it is not possible to obtain so perfect a balancing of the tubes. Consequently, it is necessary to avoid the fading effects of the pilot wave by adding an automatic high speed local gain control apparatus of the pilot signal.

For this purpose a continuous difference of potential is employed which is obtained at the point S_1 , which is the middle point, for example, of a resistance connected between the two plates of the detectors $BDEC_1$ and $BDEC_2$. This potential is applied to the detector DEC_4 so as to modify in a compensatory manner the gain of this detector and thereby the amplitude of the pilot wave applied to the apparatus F_5 and F_6 is maintained constant.

In addition to the local control of the amplitude of the pilot wave or signal, the system is provided with an automatic arrangement for the gain control of the signals transmitted. This system employs the pilot wave. Consequently 75 the detector DEC_3 is connected in parallel with

the detector DEC_4 , the same oscillator OSC being employed for the two detectors DEC_3 and DEC_4 . The pilot frequency which, in the present example, is 4 kilocycles, is filtered out by filter F_7 and amplified in AMP and rectified in R . The direct voltage obtained is employed to control the gain of the detector DEC_1 very slowly by means of special delay circuits CR_1 , CR_2 , CR_3 , which cancel the rapid variations in the amplitude of the rectified pilot signal; these variations are due to the fading phenomenon. Such control maintains the level of the signal substantially constant and prevents rapid fading phenomena from affecting the quality of the received signals. The apparatus CR_1 , CR_2 , may be formed of networks comprising capacities and condensers arranged so as to produce a current curve in function of time of suitable form and in particular such that the rate of change of gain of the receiver may be sufficiently low at any moment.

Referring now to Fig. 3 there is shown a single side-band radio receiving system in which the carrier frequency F is partly suppressed at the transmitting station and used as a pilot signal; the transmitted side-band is supposed to extend 25 between F and $F+3.000$ cycles.

The system shown in Fig. 3 is suitable for receiving facsimile, television or other similar signals on a single side-band; it is necessary therefore to synchronize the oscillator resupplying the carrier at the receiver, in the correct frequency, as well as in the correct phase. If there is no selective fading, as in the case of transmission on a wave length of 6 meters, the following equipment may be used:

The receiving antenna AR is connected through a high frequency amplifier HFA to a frequency changing detector DEC_1 . At the output of this detector, the carrier frequency is at 20 kc., and the side band extends from 20 to 23 kc. The speech signal then passes through amplifier AI and filter BF (pass-range 20 to 23 kc.) to demodulator DEM , at which point the carrier frequency is resupplied through lead l from oscillator OSC_b (frequency 20 kc.). The speech now at audio frequency is amplified to the required level by amplifier AF , to which is connected an ordinary telephone receiver TR . The beating oscillator OSC_1 is of the freely oscillating type and adjusted to $F+20$ kc. At the output of amplifier AI leads L' are branched in parallel to the input of filter BF_1 which is tuned sharply at 20 kc., therefore passes the pilot wave only, which pilot is constituted as explained above by the partly suppressed carrier of the transmitting station: 55 The output of filter BF_1 is connected to the input of detector DEC_2 at which also an E. M. F. from oscillator OSC_c is applied. Oscillator OSC_c is first adjusted approximately to a frequency of 24 kc. thus giving a beat note with the pilot at 60 4 kc. in the output of DEC_2 . The output note of 4 kc. is now amplified by amplifier A_p and is then applied to the balanced demodulator BDM_1 , BDM_2 . The grid circuits of BDM_1 are tuned respectively to 38 and 42 kc. and arranged to give equal plate outputs only when the applied E. M. F. is exactly at 4 kc. If now, for some reasons, the carrier frequency in the output of filter BF_1 is not exactly 4 kc., then the note applied to BDM_1 will not be exactly 4 kc., causing a voltage to 65 appear in the demodulator output between points a and b . This voltage is then applied through the time constant device CR_1 to the grid of a frequency control tube FCT which varies the frequency of oscillator OSC_c (frequency 24 kc.) 75

5 by means of leads l'' , in accordance with the grid bias impressed on the frequency control tube FCT; the direction of the frequency change is arranged so that the effect of any change in frequency of the pilot in the output of BF_p from exactly 20 kc., is made to change the frequency of oscillator OSC_b so as to restore the pilot exactly to 20 kc. By this means it is found in practice that the frequency difference between the oscillator 10 supplying the carrier frequency at the transmitter and the carrier locally generated at the receiver can be kept less than about 15 cycles per second.

15 To obtain exact phase between said oscillations, coupling condensers C are provided and serve as a weak coupling between the grids of oscillator OSC_b (frequency 20 kc.) and the output current from filter BF_p . The output from filter BF_p is at a frequency sufficiently near to that of oscillator 20 OSC_b to synchronize the latter automatically, by the principle of autosynchronization of coupled oscillators. This type of synchronization gives further a definite phase relation between the output of oscillator OSC_b and the incoming pilot 25 wave, which phase difference may be made equal to nought as required by suitable adjustment of the constants of oscillator OSC_b.

30 The arrangement just described in connection with Fig. 3, shows how a partly suppressed carrier wave may be used to control exactly in frequency and in phase an oscillator at a remote receiving station; an exact phase relation is maintained in this system only if the pilot wave does not fade out during even a few cycles of the controlled oscillator.

35 If a constant phase relation between the synchronized oscillators is to be maintained, even under bad selective fading conditions, two pilot frequencies at least should be used, so that if one 40 fades out at a certain moment, the controlled oscillator will be kept in phase by the second pilot, since selective fading will usually not affect equally the two pilots at the same moment.

45 In order to simplify the description, it will be assumed that the carrier frequency F is partly suppressed and is used as a first pilot wave; the second pilot will be supposed at a frequency of $F+3.4$ kc. This separation between the two 50 pilots is sufficient in general to prevent both pilots from fading out below the noise level simultaneously. The circuit as described above is used for pilot I, but in this case an automatic gain control system must be added. By this means the output 55 of amplifier A_p at 4 kc., rectified by the detector DEC_3 is made to control the grid bias of detector DEC_2 , thus, the output E. M. F. of DEC_2 is kept substantially constant in spite of variations in the input level.

60 The equipment of the transmitting station may be as shown in Fig. 1 of the accompanying drawings, but in this case the carrier wave will not be entirely balanced out, so that a portion thereof can be transmitted to the receiving station and used as a pilot wave. The second pilot will be 65 supplied by an oscillator (oscillator OSC_b in Fig. 1) as described in connection with Fig. 1. At the receiving station, the equipment will be as shown in Fig. 3 and will comprise the further equipment to be described below: First of all a gain 70 control equipment comprising a detector DEC_3 will be inserted between the demodulator DEC_2 and the balanced demodulator BDM_1 and BDM_2 to keep constant the amplitude of the first pilot wave. The filter FP_2 tuned sharply to 23.4 kc. 75 will be inserted in the output of amplifier AI .

This filter will select the second pilot which has a frequency equal to $F+3.4$ kc.

A frequency changer FG will be provided in the output of filter FP_2 , in which a frequency of 5 3.4 kc. will be produced by interaction of a frequency generated by the oscillator tube CT which is subtracted from pilot 2. A filter BF_{P1} , placed in the output of frequency changer FG is tuned sharply to 20 kc. and provides in its output a frequency equal to that of the first pilot 1. It 10 will be seen therefore that the second pilot, after traversing the path described above, will have its frequency brought to a value equal to that of pilot 2. The second pilot changes in frequency flow 15 in the output of BF_{P1} and is applied to amplifier AI_p and thus to point P and also through coupling condenser C to control oscillator OSC_b.

The oscillator CT must now be synchronized in frequency and in phase with the corresponding oscillator at the transmitting station. For 20 this purpose, a beat note is first obtained between the two pilots and this is done in detector BD through coupling condenser C_1 for pilot 1 and C_2 for pilot 2. In the output of BD there is obtained a frequency equal to 3.4 kc. which is applied 25 through an amplifier ABF associated with a filter tuned to 3.4 kc. for selecting the beat note. At this stage there is added a separate gain control equipment comprising lead L and rectifier R. The D. C. output of rectifier R controls the 30 grid bias of tube BD. In the output of ABF, a constant current is obtained; except when fading is so strong that the pilot considered is reduced below noise level. The corresponding output is applied in push-pull to the grids of a differential detector DFC. These two grids are also fed in the same phase with the output of oscillator CT by transformer T2. The D. C. voltage from the differential detector DFC is applied 35 through a time constant device or delay network 40 TCD, to the frequency controlling tube FCT, thus controlling its grid bias, and in turn controlling the frequency of oscillator CT. So, a frequency or phase change in the beat between the two pilot waves will cause the oscillator CF to change its 45 frequency and/or phase so as to restore the original relation between the beating frequencies. It will be clear, from what has been described above that, if one of the pilots fades out, the oscillator OSC_b supplying at the receiving station the partly 50 suppressed carrier will have a constant frequency and phase relation to that of the carrier frequency oscillator of the transmitting station.

The time constant of detector DEC_3 shown in 55 Fig. 3, can be made variable according to the amplitude of pilot 1. Since delay networks usually comprise inductances, capacities, and resistances and since the amount of delay provided depends upon the values chosen for these elements, it is clear that a delay variable with the amplitude of 60 the pilot wave may be provided by means of a delay network, one element (inductances, capacity, resistance) of which at least is adapted to vary in accordance with the pilot wave. For instance the inductance of the delay network may 65 be varied by means of a winding traversed by the pilot current and adapted to saturate the core of said inductance; this core may be a permalloy core. The inductance may also be varied by controlling the position in the inductance core 70 in accordance with the amplitude of the pilot wave. Similar means could be used for controlling the capacity element of the delay network. Finally the delay may be varied by controlling 75 the resistance element of the network; this may

be done for instance by associating with said resistance element the variable impedance constituted by the plate filament space of a vacuum tube, the grid of which being controlled in accordance with the amplitude of the pilot wave.

It is clear the amount of delay provided by the time constant device TCD may be controlled in accordance with the amplitude of the second pilot.

What is claimed is:

10. 1. A signaling system, subject to fading phenomena, comprising a local oscillator at a receiving station adapted to be controlled from a transmitting station by a pilot wave, and means at said receiving station adapted to continue the control on said oscillator during fading periods when the pilot wave is not received at the receiving station.
15. 2. A signaling system comprising a transmitting station, a receiving station, a local oscillator at said receiving station, means at said transmitting station for producing a pilot wave adapted to control said local oscillator, and delay devices associated with said local oscillator and adapted to be controlled in accordance with the amplitude of said pilot wave.
20. 3. A signaling system comprising means at a transmitting station for producing a pilot wave, an oscillator adapted to be controlled by said pilot wave and gain control equipment at a receiving station, and delay means associated with said equipment adapted to be controlled in accordance with the change in amplitude of said pilot wave due to fading phenomena existing between said stations.
25. 4. A signaling system comprising a transmitting station, means for generating and transmitting therefrom a signal modulated wave and two pilot waves, a receiving station, a local oscillator thereat adapted to produce a wave having the same frequency as one of said pilot waves, and means at said station whereby a wave of the frequency of the other of said pilot waves is obtained from said oscillator.
30. 5. A signaling system comprising a transmitting station, a signal source, a high frequency oscillator, means for modulating the high frequency by the signals, means for partially suppressing the unmodulated high frequency wave, means for transmitting the modulated wave and the partially suppressed unmodulated wave, and a receiving station having a local oscillator, adapted to oscillate at the same frequency as said high frequency wave and means whereby the unmodulated high frequency wave received is adapted to control said local oscillator so that it will produce the same frequency as said high frequency wave, and keep in a constant phase relation with the oscillator at said transmitting station.
35. 6. A signaling system, subject to fading phenomena, comprising an oscillator at a transmitting station and an oscillator at a receiving station, the former oscillator being adapted to control the latter, and means whereby during fading periods the difference of frequencies between the two oscillators does not exceed a predetermined limit beyond which the distortion of the transmitted signals would be intolerable.
40. 7. A signaling system comprising a receiving station adapted to receive signal waves and a pilot wave, said station having a path for said pilot wave including a quick acting gain control equipment and a path for said signal waves including a comparatively slow acting gain control equipment.

8. A signaling system subject to fading phenomena comprising a local oscillator at a receiving station adapted to be controlled from a transmitting station by a plurality of pilot waves, more than one being used to guard against the possibility of non-reception of a pilot wave which might be the case during fading periods, and separate paths for each of said pilot waves each including a gain control equipment.

9. A signaling system comprising a transmitting station having means for transmitting a signal wave and a plurality of pilot waves therefrom, more than one pilot wave being provided to guard against the possibility of the non-reception of a pilot wave in the event of fading, and a receiving station having means for detecting said waves, the means for detecting said signal wave being controlled by at least one of said pilot waves, the pilot wave exerting this control at any given time depending upon the electrical conditions existing between said stations.

10. A signaling system using modulated waves wherein at least one product of modulation, such as a side band, is suppressed at the transmitting station and the carrier wave is also suppressed or considerably attenuated before transmission in which a pilot frequency depending upon the carrier frequency is transmitted to the receiving station and used for automatically regulating the frequency of a locally generated carrier frequency characterized in this that means located at the receiving station is adapted to be variably controlled by said pilot frequency in accordance with the amount of attenuation imposed on the signals by the fading phenomena to which the system is subjected.

11. A system in accordance with claim 10 characterized in this that means are provided at the transmitting station for transmitting said pilot wave as a train of impulses.

12. A system in accordance with claim 10 characterized in this that means are provided at the transmitting station for emitting said pilot wave in the form of a sustained oscillation at comparatively high frequency modulated by a comparatively low frequency oscillation.

13. A signaling system of the single band type comprising a transmitting station, a receiving station, means for transmitting a signal carrier wave from said transmitting station to said receiving station, means for transmitting a pilot wave, having a frequency depending upon the frequency of said signal carrier wave, from the transmitting to the receiving station, a local oscillator at the receiving station for resupplying the carrier wave, means for causing said pilot wave to exert a controlling effect on said local oscillator and means comprising quick acting gain control equipment adapted to vary said effect in accordance with the amount of attenuation imposed on the signals by the fading phenomena to which the system is subjected.

14. A signaling system according to claim 13, in which means are provided at the receiving station and adapted to select the pilot wave and the received side band characterized in this, that a comparatively slow acting gain control equipment is provided in the path of the received side band.

15. A system according to claim 13 wherein means are provided at the transmitter for sending a plurality of pilot waves to the receiving station for controlling the frequency of a local oscillator used for resupplying the carrier wave, more than one pilot wave being provided so as to guard

against the possibility of the non-reception of a pilot wave which, under fading conditions, might result if only one pilot wave were used, characterized in this that further means are provided for selecting each one of said pilot waves and for applying them individually to different paths in which individual gain control equipments are provided.

16. A system according to claim 13 wherein means are provided at the transmitter for sending a plurality of pilot waves to the receiving station for controlling the frequency of a local oscillator used for resupplying the carrier wave, more than one pilot wave being provided so as to guard against the possibility of non-reception of a pilot wave which under fading conditions might result if only one pilot wave were used, means at the receiving station for selecting each one of said pilot waves and for applying them individually to different paths in which individual gain control equipments are provided, and means whereby each of said control equipments are adapted to have different time delays.

17. A signaling system subject to fading phenomena comprising a transmitting station, a receiving station, an oscillator at said receiving station, means at said transmitting station for producing a plurality of pilot waves, more than one pilot wave being provided to ensure that, if fading exists between said stations, at least one pilot wave will not become obliterated and will be received at the receiving station, means at said receiving station adapted to change the frequency of one of said pilot waves, and means whereby said changed frequency is adapted to control said oscillator.

18. A system in accordance with claim 17 having an oscillator at the transmitting station, an oscillator at the receiving station intended to operate in synchronism with the oscillator at the transmitting station, and means for producing a beat note between said pilot waves for effecting such synchronism.

19. A system in accordance with claim 17 characterized in this that means are provided at the transmitting station whereby the frequencies of said pilot waves are regularly spaced in the frequency spectrum.

5

20. A signaling system comprising a transmitting station, a high frequency oscillator thereat, a signal source, means for modulating the high frequency produced by said oscillator by the signals and for transmitting the modulated wave, means for also transmitting a pilot wave and a receiving station having means controlled by said pilot wave for effecting gain control of the received signals and having a local oscillator with which is associated means under the control of the pilot wave, adapted to compensate for fading effects between said stations.

10

21. A system in accordance with claim 20, wherein gain control equipment is provided in the path of the pilot wave and means under the control of the amplitude of the pilot wave for delaying the operation of said gain control equipment.

15

22. A system in accordance with claim 20, characterized by means for rendering gain control equipment in the path of the signals variable in accordance with the average amplitude of received signals.

20

23. A system in accordance with claim 20 wherein means is provided for transmitting a plurality of pilot waves to said receiving station, more than one pilot wave being supplied in order to ensure that, when fading exists between said stations, at least one of the pilot waves will reach the receiving station at a sufficient amplitude to be detected, means at the receiving station for converting the received pilot waves to a predetermined frequency, and means whereby said frequency is adapted to control said oscillator.
